UNITED STATES PATENT OFFICE.

HENRY W. SCHNEIDER, OF LITTLE OLEY, PENNSYLVANIA.

DESIGN FOR AN INKSTAND.

SPECIFICATION forming part of Design No. 21,990, dated November 15, 1892.

Application filed August 22, 1892. Serial No. 443,803. Term of patent 7 years.

To all whom it may concern:

Be it known that I, HENRY W. SCHNEIDER, a citizen of the United States, residing at Little Oley, in the county of Berks and State of Pennsylvania, have invented a new and original Design for Inkstands, of which the following is a specification.

The accompanying drawing shows a perspective view of the inkstand.

The body of the ink-receptacle A is egg-shaped and stands upright with its tapered or pointed end resting on and in contact with a suitable base C. The large or butt end of the egg-shaped receptacle is uppermost, and a horizontal line d bisects the said upper end.

The base has two lateral brackets e for the support of a penholder. The ink-receptacle has the outline of the perfect egg or unbroken egg standing, with its rounded point resting on a base and without any other support. ²⁰

I claim and desire to secure by Letters Patent—

The design for inkstands, substantially as herein shown and described.

In testimony whereof I affix my signature in ²⁵ the presence of two witnesses.

HENRY W. SCHNEIDER.

Witnesses:

WILLIAM FLOYD,
L. P. G. FEGLY.
